US0D1000199S

(12) **United States Design Patent** (10) **Patent No.:** **US D1,000,199 S**
(45) **Date of Patent:** **** Oct. 3, 2023**

(54) **COMBINED LID WITH MOUTHPIECE AND CAP**

(71) Applicant: **MiiR Holdings, LLC**, Seattle, WA (US)

(72) Inventors: **Geoff Henkel**, Redmond, WA (US); **Bryan Papé**, Seattle, WA (US)

(73) Assignee: **MiiR Holdings, LLC**, Seattle, WA (US)

(**) Term: **15 Years**

(21) Appl. No.: **29/785,338**

(22) Filed: **May 25, 2021**

(51) LOC (14) Cl. **07-99**

(52) U.S. Cl.

USPC **D7/396.2; D7/392**

(58) **Field of Classification Search**

USPC D7/392, 387, 396.1, 396.2, 397, 509,

D7/510, 511, 543; D9/435

CPC B65D 41/04; B65D 41/00; B65D 41/02;

A47G 19/22; A47G 19/2205; A45F 3/16;

(57) **CLAIM**

The ornamental design for a combined lid with mouthpiece and cap, as shown and described.

DESCRIPTION

FIG. 1 is a perspective view of a combined lid with mouthpiece and cap shown in an open configuration showing our new design;

FIG. 2 is a front, elevation view thereof;

FIG. 3 is a rear, elevation view thereof;

FIG. 4 is a left, elevation view thereof;

FIG. 5 is a right, elevation view thereof;

FIG. 6 is a top, plan view thereof;

FIG. 7 is a bottom, plan view thereof;

FIG. 8 is a perspective view of a combined lid with mouthpiece and cap shown in an closed configuration showing our new design;

FIG. 9 is a front, elevation view thereof;

FIG. 10 is a rear, elevation view thereof;

FIG. 11 is a left, elevation view thereof;

FIG. 12 is a right, elevation view thereof;

FIG. 13 is a top, plan view thereof; and,

FIG. 14 is a bottom, plan view thereof.

The broken lines in the drawing views depict portions of the combined lid with mouthpiece and cap that form no part of the claimed design.

1 Claim, 8 Drawing Sheets
